CLAIM

The ornamental design for an espresso coffee machine, as shown and described.

DESCRIPTION

FIG. 1.1 is a front, right, and top perspective view of the espresso coffee machine showing our new design;

FIG. 1.2 is a right side elevation view thereof;

FIG. 1.3 is a left side elevation view thereof;

FIG. 1.4 is a top plan view thereof;

FIG. 1.5 is a bottom plan view thereof;

FIG. 1.6 is a front elevation view thereof; and

FIG. 1.7 is a rear elevation view thereof.

The broken lines and the areas within them depict portions of the espresso coffee machine that form no part of the claim.
